UNITED STATES PATENT OFFICE.

WILHELM DAUMANN, OF HAMBURG, GERMANY, ASSIGNOR TO C. H. F. MÜLLER, RÖNTGENRÖHRENFABRIK, OF HAMBURG, GERMANY, A CORPORATION OF GERMANY.

ELECTRON TUBE.

Application filed January 16, 1923, Serial No. 613,045, and in Germany January 14, 1922.

My invention relates to improvements in electron tubes. As is known in the art, a discharge of electric energy may occur between electrodes in a high vacuum—where ionization of the gas is impossible—without auxiliaries such as an incandescent cathode etc. The condition for such a discharge is that the electrodes should be at a sufficiently short distance from one another. The discharge is 10 a pure electron discharge and may therefore be used technically for all purposes where cathode rays are employed.

The discharge is assisted by sharply curved faces of the electrodes, such as edges, 15 points, etc.

In my invention, I make the said sharply curved faces from at least one thin wire the enveloping surfaces of which face the electrode. In its most primitive construction, 20 my improved device therefore comprises a metal plate anode arranged in a high vacuum electron tube, and a thin wire cathode secured by any convenient means at a short distance from said anode, its enveloping surface 25 facing the anode. Experience has demonstrated that a thin wire supported in this manner at a distance of a few millimetres from a plate is able to effect a discharge of the kind described, if a suitably high voltage 30 be impressed.

The advantages of my novel device are as follows:

1. The difficulty of constructing the active faces of cathodes in the shape of edges, points 35 or the like, is removed by using wire which readily lends itself to any desired form.

2. In my improved device, the radii of the active faces of a wire can be duplicated with any desired degree of accuracy so that with 40 my improved device I am able to manufacture tubes having exactly identical electric properties.

3. The complete degasification of the electrodes required in tubes of the kind described 45 may readily be effected in the cathode by means of currents conducted through the wires.

4. The wires may be used as incandescent wires as well, so that the discharge tube may 50 also be operated as an incandescent cathode tube, an important advantage, particularly when degasifying the other electrodes, for instance the anode.

In the case of high voltages, such as are

required in the generation of very hard 55 Roentgen rays, for instance, the wires having the sharply curved faces should be so arranged as not to be torn by the strong electrostatic attraction then arising. To this end, in my improved device, I form the wires 60 as sharply curved bends having radii of a few millimetres, and facing the other electrode. The tensile stress on the wires is reduced so considerably by these means that the wires are not torn with the voltages occurring, as demonstrated by theory and practical experience. 65

In the drawings affixed to this specification, I have illustrated several devices embodying my invention by way of example. 70 In the drawings—

Fig. 1 is an elevation showing a high vacuum tube provided with my improved device, and its connections,

Figs. 2 and 3 are elevations illustrating 75 two modified tubes, partly broken away, and

Fig. 4 is an isometric view of a portion of the tube shown in Fig. 3.

Referring to Fig. 1, this tube comprises a plate 1 which may be circular, and, facing 80 said plate, a curved wire 2 which is secured to the leads 3, 4. The curved wire 2 is in a plane at right angles with the plate 1 from which its vertex is at a distance of a few millimetres. 85

For degasifying the wire 2, current is conducted through it from a heating battery 5 by means of the leads 3, 4. The plate 1 is degasified by the electrons emanating from the hot wire 2 and are projected on to the 90 plate 1 with the aid of the high voltage generator 6.

For higher loads, the anode plate 1 is made larger and a system of wires is arranged facing it. 95

In order to utilize also the cathode rays which, as experience shows, emanate laterally, dished or hollow anodes are provided in the tubes illustrated in Figs. 2 and 3, the bends of the wires being arranged in said 100 hollow anodes.

As shown in Fig. 2, the anode 7 is in the shape of a hollow hemisphere and three bent wires 8 are arranged in it the bent portions of which extend in principal planes of the 105 sphere and substantially concentrically to it.

In the tube illustrated in Figs. 3 and 4, the anode 9 is a semicylinder and in it are

arranged a plurality of wires 10, curved as described, which extend in planes at right angles with the surface of said cylinder and its axis and are supported by wires 11 embedded in an insulated member 12 at the cathode end of the tube.

In the tubes illustrated in Figs. 2 to 4, the curved wires 10 are connected in series with current leads 13 and 14 so that they can be heated to incandescence by means of currents conducted through them, when required, so as to degasify the wires themselves and to be employed as source of electrons for degasifying the anode by electrons projected on to it.

I claim:

A vacuum tube comprising an evacuated envelope having re-entrant stems, a hollow anode supported by one of said stems, a filamentary cathode closely adjacent said anode and supported by the other of said stems, said cathode being composed of a series of hair-pin-like loops the ends of which are embedded in its supporting stem, portions of the loops being connected in series by connecting links. 20 25

In testimony whereof I hereunto affix my signature.

WILHELM DAUMANN.
